Primary Examiner—Celia A Murphy(74) *Attorney, Agent, or Firm*—Porter, Wright, Morris & Arthur, LLP(57) **CLAIM**

The ornamental design for a shoe sole, as shown and described.

DESCRIPTION

FIG. 1 is a perspective view of a shoe sole according to my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom plan view thereof; and,

FIG. 7 is a bottom plan view of an alternative embodiment of the shoe sole according to the present invention, the appearance of the shoe sole being identical to the first embodiment except for an indication of surface contrast.

The uppermost broken line in FIGS. 1 through 4 define the boundary of the design; the broken lines and the areas within them, forming no part of the claim.
